T. W. ROLPH & W. LUMLEY.
LIGHTING ATTACHMENT.
APPLICATION FILED NOV. 8, 1915.

1,294,306.

Patented Feb. 11, 1919.

INVENTORS:
THOMAS W. ROLPH,
WILFRED LUMLEY,
BY *Albert S. Davis*
THEIR ATTORNEY.

UNITED STATES PATENT OFFICE.

THOMAS W. ROLPH AND WILFRID LUMLEY, OF CLEVELAND, OHIO, ASSIGNEES TO
GENERAL ELECTRIC COMPANY, A CORPORATION OF NEW YORK.

LIGHTING ATTACHMENT.

1,294,306.

Specification of Letters Patent. Patented Feb. 11, 1919.

Application filed November 8, 1915. Serial No. 60,199.

To all whom it may concern:

Be it known that we, THOMAS W. ROLPH and WILFRID LUMLEY, citizens of the United States, residing at Cleveland, county of 5 Cuyahoga, State of Ohio, have invented certain new and useful Improvements in Lighting Attachments, of which the following is a specification.

Our invention relates to lighting attachments, and more particularly to lighting attachments for machines. An object of our invention is to provide a lighting attachment which is capable of ready adjustment so that the light may be concentrated upon any desired portion of the machine, and particularly upon the mechanism thereof which operates directly upon the work. A further object of our invention is to provide an attachment which may be readily attached to 20 or detached from machines now upon the market.

Our invention is particularly adapted for use in connection with machines comprising an arm carrying a mechanism at one end thereof. Our attachment comprises an arm which may be pivotally mounted at the same end with the aforesaid mechanism, and which is adapted to swing in a plane substantially parallel with said arm. The attachment 30 arm has pivotally connected thereto a light source which is adapted to swing in a plane substantially at right angles to the first-mentioned plane. In the case of machines, such as sewing machines, having a substantially horizontally extending arm carrying a mechanism, such as a needle-bar mechanism, at one end thereof, the attachment arm is pivotally mounted above the said mechanism so as to swing in a substantially horizontal 40 plane. The light source in such case is pivoted to the attachment arm so as to swing in a substantially vertical plane. Our attachment is preferably provided with means for clamping the attachment arm in any desired position, and the said clamping means is preferably such as to allow the ready removal of the attachment arm and so of the lighting attachment as a whole. In the case of sewing machines the plate or other device upon which the attachment arm is pivoted is preferably secured to the cover plate of the needle-bar casing. This may ordinarily be done without necessitating any alteration of the original machine as one of

the screws of the cover plate may be utilized 55 for this purpose.

Further features and advantages of our invention will appear from the more detailed description which follows and from a reference to the accompanying drawing, in 60 which Figure 1 is a perspective of a portion of a sewing machine having one form of our lighting attachment applied thereto; Fig. 2 is an elevation, partly in section, of the main portion of our attachment, and 65 Fig. 3 is a plan view of the same.

Referring now to the drawing, the sewing machine 10 is provided with the ordinary arm 11, which carries at one end thereof the needle bar casing 12. An attaching means 70 such as the angle plate 13 is secured to the face plate 14 of the needle bar casing, as by a screw 15, which is preferably one of the screws which is ordinarily used for securing the said face plate to the casing. The plate 75 13 extends over the top of the casing and carries a vertically extending stud 15'. A horizontally extending arm 16 is provided with a sleeved end 17, which passes over the stud 15'. The latter is screw threaded at 18 80 and a thumb nut 19 engages therewith, and by this means the arm 16 may be clamped in any desired position, or by loosening the said nut the arm may be moved to any desired position in a horizontal plane. Pivoted to the 85 other end of the arm 16 is an angle-plate 20 which carries the lamp socket 21, being perforated to receive the conductor cord 22. The socket 21 preferably supports a reflector 23. This is preferably of the concentrating 90 type and may be provided with ventilating openings 24. Preferably these are formed by cutting and pressing in the metal from below, thus protecting the eyes of the operator from the light. A suitable support 25 95 is provided for the cord 22 on the vertically extending portion of the arm 11. A support ring 26 is carried by the thumb nut 19, being attached to the ring 27, which is loosely held in a groove in the said thumb nut. 100

It will be apparent that the arm 16 can be turned to any position in a horizontal plane so that the light may be thrown upon the needle from any desired direction. By tilting the angle-plate 20 the position of the 105 lamp may be adjusted in a vertical plane. By swinging the arm 16 to a position more or less transverse to the arm 11 and suitably

adjusting the angle-plate 20, the light may be directed upon work held in the lap of the operator or toward any other desired point away from or upon the machine.

5 The construction is such that the lamp can be readily removed from the machine and fastened to any other point, as to a window sill, to be used as a reading lamp. It will be apparent also that the construction is such 10 that the bracket may be swung in close to the arm of the machine so that, as in the case of folding machines, the machine can be closed with the complete outfit inside.

What we claim and desire to secure by 15 Letters Patent of the United States, is:

1. A lighting attachment, adapted to be mounted on the needle bar casing of a sewing machine, comprising a plate, a vertical stud fixed to said plate, a horizontal bracket 20 arm carrying an incandescent lamp at one end and sleeved at the other on said stud for adjustment in the horizontal plane, said stud

being screw-threaded and adapted to receive a holding and clamping thumb nut for facilitating the removal of said lamp and 25 clamping the same in various horizontal positions, and a cord-holding attachment carried by said stud.

2. A lighting attachment adapted to be mounted on the head of a sewing machine, 30 comprising an attachable angle plate, a vertically disposed stud fixed to said plate, a horizontally extending bracket arm sleeved at one end on said stud and carrying at the other end an incandescent lamp pivoted for adjustment in the vertical plane, and a thumb nut adapted to be screwed on to said stud for clamping said arm in various horizontal positions and facilitating the removal 35 thereof from the machine. 40

In witness whereof, we have hereunto set our hands this fifth day of November, 1915.

THOMAS W. ROLF.
WILFRID LUMLEY.
